DISPLAY RACK

Wilbur R. Minton, Sidney, Ohio

Application July 15, 1936, Serial No. 90,739

2 Claims. (Cl. 211—135)

This invention relates to a display rack.

It is an object of my invention to provide such a rack which is capable of presenting actual merchandise of varying descriptions, arranged at different levels, convenient to the angle of vision of the prospective buyer.

It is a further object of this invention to provide such a rack wherein the price of the goods will be likewise conveniently displayed to the angle of vision of the prospective buyer.

It is a further object of this invention to provide such a rack wherein packaged goods or merchandise is presented at different levels for ease of removal by the prospective purchaser.

It is a further object of this invention to provide such a rack of cheap construction of great strength, with little weight and with a low center of gravity, wherein merchandise and/or packaged goods of varying shapes and sizes may be displayed.

It is a further object of this invention to provide such a display rack which may be easily cleaned and which is thus highly sanitary and in which is incorporated no fragile material, such as glass, to be broken by the feet, umbrellas, baskets, etc. of the prospective purchasers.

It is a further object of this invention to provide such a display rack wherein the merchandise and/or packaged goods may be conveniently and compactly stored and from which removal thereof is facilitated.

It is a further object of this invention to provide such a structure wherein fancy, ornate design is obviated and wherein the danger to prospective purchasers, due to snagging of apparel is obviated by the avoidance of projections.

It is a further object of this invention to provide such a structure wherein a construction is utilized, which facilitates the use of contrasting colors to enhance the appearance of the merchandise and/or packaged goods and of price tags adjacent thereto.

It is a further object of this invention to provide such a structure wherein means is provided for easy attachment and detachment of price tags and/or labels to and from a part of the structure adjacent the goods displayed.

It is a further object of this invention to provide such means whereby the price tag and/or label may be presented to the vision of a prospective purchaser at an angle substantially parallel to the angle of presentation of the goods to which price tags and/or labels refer.

These and other advantages will appear from the following description taken in connection with the drawing.

In the drawing:

Figure 1 is a perspective view of a display rack

constructed according to the principles of my invention;

Figure 2 is an end elevational view of the structure illustrated in Figure 1; and

Figure 3 is a sectional view in elevation taken on the line 3—3 of Figure 1.

Referring to the drawing in detail, the framework of the display rack comprises a vertical rear panel 1, to the ends of which is suitably attached, by means of bolts, rivets or the like, a pair of angles 2 of L-section. For the purpose of additional strength, a central angle member 3, likewise of L-section, is secured, in vertical disposition, to the central portion of the panel 1.

Side panels 4 are attached at their rear ends to the forwardly extending sides of the angles 2. These side panels 4 extend substantially two-thirds as high as the rear panel 1. Also attached to the forward and top inner edges of the side panels 4 are angles 5 which follow the forward and top outlines of the side panels 4 and which are rigidly secured at their top rear ends to the angles 2.

An angle 6, similar to the angles 5, is preferably secured midway of the structure, at its upper rear end to the angle 3. Similar brackets 7 are secured at their ends respectively to the angles 2 and 5 and to the angles 2 and 6. These brackets 7 provide a support for the lower shelf of the display rack, as will be hereinafter more clearly described. The forward top corners of the side panels 4 are inclined in order to accommodate the intermediate shelf 8 which is secured to the top surfaces of the angles 5 and 6.

The shelf 8 which is horizontal is preferably formed integrally with a diagonal shelf portion 9 which is suitably inclined to the horizontal and which diagonal shelf 9 is provided with a continuation in the form of a perpendicular extension 10 which terminates in a flange 11 which is substantially parallel to the diagonal shelf 9. Vertical bent-up portions 12 are provided at the ends of the diagonal shelf 9.

The flange 11 is provided with a channel member 11a having its upper and lower edges bent over upon themselves to provide a channel for slidably supporting price tickets or cards. The tickets or cards may be inserted at the ends of member 11a and adjusted longitudinally thereof until disposed adjacent, and in front of, the merchandise to which they refer.

Rigidly secured to the brackets 7 in the same manner in which the shelf 8 is secured to the angles 5 and 6 is a substantially horizontal shelf 13, with which is integrally formed a diagonal shelf 14 somewhat similar to the diagonal shelf 9. The diagonal shelf 14 has a perpendicular continuation 15 similar to the continuation 10 of the diagonal shelf 9 which terminates in the flange 16 which is substantially parallel to the

diagonal shelf 14. The flange 16 is provided with a channel member 16a similar to the channel member 11a and disposed in the same relation with respect thereto.

5 As will clearly appear from Figures 2 and 3, the diagonal shelves 9 and 14 are disposed at different angles to the horizontal, the shelf 14 being more nearly horizontal, for reasons which will hereinafter more clearly appear. Below the 10 lower shelf and rigidly secured to the angles 5 and 6 is the front panel 17.

Attached at their rear ends to the top ends of the angles 2 and 3 are horizontally disposed angles 18 which are supported at their forward 15 ends by the vertically disposed standards 19. The standards 19 rest upon the horizontal portion 8 of the intermediate shelf and are rigidly secured to this portion 8 and the upper surfaces of the angles 5 and 6 therebeneath. Rigidly secured 20 to the horizontally disposed flanges of the angles 18 is the top shelf 19a which is preferably in the form of a solid panel. A strip 20 is secured to the forward surface of the upper end of each of the standards 19. Secured to this strip 20, 25 by means of bolts, rivets or the like, is a channel member 21 having its top and bottom edges bent over upon themselves and forwardly disposed in order to provide means for slidably supporting price tickets or cards which may be inserted at 30 the ends of these members and adjusted longitudinally in the channel formed therein, as may be desired.

As before stated, the diagonal shelves or shelf portions 9 and 14 and their substantially parallel flanges 11 and 16 are disposed at different angles to the horizontal, the angularity of the shelf 9 being greater than that of the shelf 14. The channel member 21 is preferably at the normal eye level of the prospective purchaser. Although the eye level will vary somewhat, a mean eye level has been chosen. The prospective purchaser may be expected to pass rather close to the display rack and, during this passage, the eye of the purchaser may, due to the preferred 45 angularity of the diagonal shelves 9 and 14, sweep downwardly from the substantially horizontal angle, at which the channel member 21 is presented, to the diagonal shelf 9, its flange 11 and price tickets supported in channel member 11a and thence to the diagonal shelf 14 and its flange 16 and price tickets supported in channel member 16a thereon.

Merchandise such as cans or packages are 50 preferably stacked in reserve upon the horizontal portions 8 and 13 of the lower and intermediate shelf and upon the top shelf 18. Other packages or cans are placed forwardly of the 55 reserve cans or packages upon the diagonal shelves 9 and 14.

60 The display rack disclosed is particularly suitable for use in stores or shops of self-service type, and the particularly desirable features of the display rack are that the goods are supported within easy reach and in the normal field of vision of the prospective purchaser. Furthermore, the provision of storage space upon the 65 horizontal portions 8 and 13 of the shelves below the normal horizontal line of vision increases the field of vision of the article so displayed and likewise provides a reserve from which the shelves 9 and 14 may conveniently be kept filled by the attendant.

An additional feature of the display rack is 70 the accessibility for the purpose of cleaning and 75 for the purpose of repainting. The use of a

white background for the display of colored can goods and other highly colored packages has been found extremely effective. Likewise, the use of black upon the flanges 11 and 16, their associated channel members 11a and 16a, and the continuations or extensions 10 and 15 for the purpose of providing contrast for price tags, tickets or labels has been found extremely effective.

10 The use of display racks constructed according to the principles of my invention results in a greater economy of floor space than has been heretofore achievable. The provision of storage space in the display racks makes replacement of the display easy and quick. The utmost degree of visibility of the merchandise is provided and the low cost of manufacture makes the display rack available to merchants who have been heretofore prevented from purchasing needed equipment of this character because of the 15 former great expense of such equipment.

15 It will be understood that the above-described structure is merely illustrative of one manner in which my invention may be carried out and that I desire to comprehend within my invention such modifications as may be within the 20 scope of the claims and the invention.

Having thus fully described my invention, what I claim as new and desire to secure by Letters Patent is:

30 1. A display rack for packaged goods having three shelves and a back wall secured to all of said shelves and providing a back wall for each of the lower two shelves, one of said shelves being disposed horizontally at substantially eye level, the second of said shelves being disposed slightly below the horizontal eye level and having a diagonal portion substantially perpendicular to the angle of vision, the third of said shelves being disposed below said second shelf and having a diagonal portion nonparallel to the diagonal portion of said second shelf, the plane of the diagonal portion of said third shelf being substantially perpendicular to the normal angle of vision, supporting standards secured between the front of said first shelf and said second shelf for cooperation with said back wall to rigidly support said first and second shelves with respect to one another, and common end walls rigidly secured to said second and third named shelves respectively and adapted to cooperate with said common back wall to rigidly support said second and third named shelves in fixed spaced relationship.

35 2. A display rack for packaged goods having three shelves connected by a back wall rigidly secured thereto, one of said shelves being disposed horizontally at substantially eye level, the second of said shelves being disposed slightly below the horizontal eye level and having the diagonal portion substantially perpendicular to the angle of vision, the third of said shelves being disposed below said second shelf and having a diagonal portion nonparallel to the diagonal portion of said second shelf, the plane of the diagonal portion of said third shelf being substantially perpendicular to the normal angle of vision, said second and third shelves being provided at each end with a common end wall rigidly secured thereto, and supporting brackets rigidly secured between said first and second shelves, said back wall, said end walls and said brackets cooperating to rigidly connect said shelves in spaced relationship.
